CLAIM

The ornamental design for a portable bluetooth speaker with removable battery, as shown and described.

DESCRIPTION

FIG. 1 is a top, front perspective view of a portable bluetooth speaker with removable battery showing my new design;
FIG. 2 is a front view thereof;
FIG. 3 is a rear view thereof;
FIG. 4 is a right side view thereof;
FIG. 5 is a left side view thereof;
FIG. 6 is a top view thereof;
FIG. 7 is a bottom view thereof;
FIG. 8 is a cross-sectional view thereof along line 8-8 in FIG. 3; and,
FIG. 9 is a cross-sectional view thereof along line 9-9 in FIG. 4.
The broken lines in the drawings illustrate environmental material that forms no part of the claimed design.
